UNITED STATES PATENT OFFICE

123,287

DESIGN FOR A TEXTILE FABRIC OR SIMILAR ARTICLE

Allan E. Bernstein, Woodmere, N. Y., assignor to
S. Stein & Co., New York, N. Y., a firm composed of Henry Bernhard, Leon S. Hartman, and Herman W. Block

Application September 28, 1940, Serial No. 95,512

Term of patent 3½ years

To all whom it may concern:

Be it known that I, Allan E. Bernstein, a citizen of the United States of America, residing at Woodmere, Long Island, New York, have invented a new, original, and ornamental Design for a Textile Fabric or Similar Article, of which the following is a specification, reference being had to the accompanying drawing, forming a part thereof.

The figure is a plan view of a textile fabric showing my new design. The dot and dash lines on the drawing outline substantially a design unit, which unit is repeated in regular succession as indicated by the extensions beyond the unit boundaries.

I claim:

The ornamental design for a textile fabric or similar article, as shown and described.

ALLAN E. BERNSTEIN.
